E. H. BROWN

HYDRAULIC TURBINE

Filed July 1, 1921

UNITED STATES PATENT OFFICE.

EDWIN H. BROWN, OF MILWAUKEE, WISCONSIN, ASSIGNOR TO ALLIS-CHALMERS MANUFACTURING COMPANY, OF MILWAUKEE, WISCONSIN, A CORPORATION OF DELAWARE.

HYDRAULIC TURBINE.

Application filed July 1, 1921. Serial No. 481,785.

To all whom it may concern:

Be it known that EDWIN H. BROWN, a citizen of the United States, residing at Milwaukee, in the county of Milwaukee and

5 State of Wisconsin, has invented a certain new and useful Improvement in Hydraulic Turbines, of which the following is a specification.

This invention relates in general to improvements in the art of converting hydraulic potential energy into kinetic energy or useful work, and relates more specifically to improvements in the construction and operation of hydraulic energy converting 10 apparatus such as hydraulic turbines.

An object of the invention is to provide hydraulic energy converting apparatus which is simple in construction and efficient in operation. Another object of the 15 invention is to provide a hydraulic turbine which is capable of efficiently converting the energy of a whirling mass or stream of liquid into rotary motion of the turbine rotor. A further object of the invention is to provide an exceedingly simple and strong 20 turbine impeller especially adapted for use in connection with high speed hydraulic apparatus. Still another object of the invention is to provide a turbine which is especially adapted to convert into useful 25 work the energy of water at hydraulic power sites where the available head is low and the water supply is abundant. A further object is to provide a turbine having enormous discharge capacity. These and 30 other objects and advantages of the present invention and the manner of their attainment will be apparent from the following description.

40 A clear conception of a number of embodiments of the present invention and of the operation of devices constructed in accordance therewith, may be had by referring to the drawing accompanying and forming a part of this specification, in which like reference characters designate the same or similar parts in the various views.

Fig. 1 is a plan view of one form of impeller embodying the present invention.

Fig. 2 is a plan view of another form of impeller embodying the present invention.

Fig. 3 is a plan view of still another form of impeller embodying the present invention.

Fig. 4 is a plan view of another form of impeller embodying the present invention.

Fig. 5 is a side elevation of the form of impeller shown in plan view in Fig. 1.

Fig. 6 is a side elevation of the form of impeller shown in the plan view in Fig. 2.

Fig. 7 is a side elevation of the form of impeller shown in the plan view in Fig. 3.

Fig. 8 is a side elevation of the form of impeller shown in the plan view of Fig. 4.

Fig. 9 is a central vertical section through a hydraulic turbine installation embodying an impeller such as illustrated in Figs. 1 and 5.

Fig. 10 is a central vertical section through an inverted hydraulic turbine installation embodying an impeller similar to that disclosed in Fig. 9.

Fig. 11 is a central vertical section through an inverted hydraulic installation embodying an impeller similar to that disclosed in Fig. 10.

The runner or impeller 10 illustrated in detail in Figs. 1 and 5, comprises an upwardly converging conoidal hub 12 and a series of four dished vanes 11 having inner extremities rigidly attached to the hub 12. As clearly shown in Fig. 1, each vane 11 is curved longitudinally, thus forming a pocket, but the adjacent vanes 11 do not overlap when projected upon a plane perpendicular to the impeller axis. As clearly shown in Fig. 5, each vane 11 is twisted thus giving it varying angularity relatively to a plane perpendicular to the impeller axis, the vane angle gradually increasing as the hub 12 is approached. The outer extremities or ends 13 of the vanes 11 are free, being bounded by fragments of a cylindrical surface having straight line generatrices parallel to the impeller axis. The hub 12 of the rimless impeller 10 thus formed, is bored for attachment to a supporting shaft.

The runner or impeller 20 illustrated in detail in Figs. 2 and 6, comprises an upwardly converging conoidal hub 22 and a series of four dished vanes 21 having inner extremities rigidly attached to the hub 22. As clearly shown in Fig. 2, each vane 21

is curved longitudinally, thus forming a pocket, but the adjacent vanes 21 do not overlap when projected upon a plane perpendicular to the impeller axis. As clearly 5 shown in Fig. 6, each vane 21 is twisted thus giving it varying angularity relatively to a plane perpendicular to the impeller axis, the vane angle gradually increasing as the hub 22 is approached. The outer extremities or 10 ends 23 of the vanes 21 are free, being bounded by fragments of upwardly converging conical surfaces having straight line generatrices which intersect the impeller axis above the vanes 21. The hub 22 of 15 the rimless impeller 20 thus formed, is bored for attachment to a supporting shaft.

The runner or impeller 30 illustrated in detail in Figs. 3 and 7, comprises an upwardly converging conoidal hub 32 and a 20 series of four dished vanes 31 having inner extremities rigidly attached to the hub 32. As clearly shown in Fig. 3, each vane 31 is curved longitudinally, thus forming a pocket, but the adjacent vanes 31 do not 25 overlap when projected upon a plane perpendicular to the impeller axis. As clearly shown in Fig. 7, each vane 31 is twisted thus giving it varying angularity relatively to a plane perpendicular to the impeller axis, 30 the vane angle gradually increasing as the hub 32 is approached. The outer extremities or ends 33 of the vanes 31 are free, being bounded by fragments of a downwardly converging conical surface having straight line 35 generatrices which intersect the impeller axis below the vanes 31. The hub 32 of the rimless impeller 31 thus formed, is bored for attachment to a supporting shaft.

The runner or impeller 40 illustrated in detail in Figs. 4 and 8, comprises an upwardly converging conoidal hub 42 and a 40 series of four dished vanes 41 having inner extremities rigidly attached to the hub 42. As clearly shown in Figs. 4, each vane 41 is curved longitudinally, thus forming a pocket, but the adjacent vanes 41 do not 45 overlap when projected upon a plane perpendicular to the impeller axis. As clearly shown in Fig. 8, each vane 41 is twisted thus giving it varying angularity relatively 50 to a plane perpendicular to the impeller axis, the vane angle gradually increasing as the hub 42 is approached. The outer extremities or ends 43 of the vanes 41 are 55 free, being bounded by surfaces which are curved both vertically and horizontally thereby eliminating sharp corners at the ends of the vanes 41. The hub 42 of the rimless impeller 40 thus formed, is bored 60 for attachment to a supporting shaft.

The hydraulic installation disclosed in Fig. 9 comprises means forming an annular horizontal inlet conduit 2 adapted to conduct liquid inwardly toward the central axis 65 of the installation, means forming a spiral

collecting and diffusing discharge conduit 4 located below and arranged concentric with the inlet conduit 2, means forming a vane free transition space 3 located between the inlet and discharge conduits 2, 4 and 70 adapted to change the direction of flow of the liquid admitted through the inlet conduit 2 from inward to substantially axial flow and to subsequently conduct the liquid in a substantially axial direction, means 75 forming an annular diffusing conduit 8 located between the transition space 3 and the discharge conduit 4 and adapted to decelerate the flow of liquid delivered outwardly toward the discharge conduit 4, and an im- 80 peller 10 located between the transition space 3 and the diffusing conduit 8. Within the inlet conduit 2 is located an annular series 85 of guide vanes 5 having vertical adjusting pivots 9, these guide vanes 5 serving the dual function of varying the degree of whirl of the liquid admitted to the transition space 3 and of controlling the quantity of liquid admitted to the turbine impeller. The transition space 3 is bounded along its upper and central portions by a conoidal wall 6, one function of which is to gradually 90 change the direction of flow of the liquid passing through the transition space 3, from inward to substantially axial. liquid delivered outwardly toward the discharge conduit 54, and an inverted impeller 50 located between the transition space 53 and the diffusing conduit 58. The spiral inlet conduit 52 is preferably provided with a valve for controlling the admission of liquid thereto. The lower portion of the transition space 53 is bounded adjacent to the central axis, by a conoidal wall 56 one function of which is to gradually change the direction of flow of the liquid passing through the transition space 53, from inward to substantially axial. The inverted impeller 50, the specific construction of which is similar to that of the impeller 10, is rotatably supported by the vertical main shaft 57 having a bearing in the casing which forms the discharge conduits 58, 54, the upper extremity of the shaft 57 being either directly or indirectly associated with a suitable energy absorber. The impeller 50 and the conduits leading to and from the same are inclosed by a sectional casing the sections of which are readily removable in order to permit assembly and dismantling of the unit, and the lower portion of which in the specific embodiment shown, co-operates with a concrete foundation to form the inlet conduit 52.

39 The inverted hydraulic installation disclosed in Fig. 11 comprises means forming an annular horizontal inlet conduit 62 adapted to conduct liquid inwardly toward the central axis of the installation, means forming a spiral collecting and diffusing discharge conduit 64 located above and arranged concentric with the inlet conduit 62, means forming a vane free transition space 63 located between the inlet and discharge conduits 62, 64 and adapted to change the direction of flow of the liquid admitted through the inlet conduit 62 from inward to substantially axial flow and to subsequently conduct the liquid in a substantially axial direction, means forming an annular diffusing passage 68 located between the transition space 63 and the discharge conduit 64, and adapted to decelerate the flow of liquid delivered outwardly toward the discharge conduit 64, and an impeller 60 located between the transition space 63 and the diffusing conduit 68 and partially surrounded by a stationary substantially cylindrical wall 70. Within the inlet conduit 62 is located an annular series of guide vanes 65 having vertical adjusting pivots 69, these vanes 65 serving a dual function of varying the degree of whirling of the liquid admitted to the transition space 63 and of controlling the quantity of liquid admitted to the turbine impeller. The transition space 63 is bounded adjacent to the central axis of the unit, by an upwardly converging conoidal wall 66 one function of which is to gradually change the direction of flow of liquid passing through the transition space 63, from inward to substantially axial. The impeller 60 the specific construction of which is similar to that of the impeller 50, is rotatably supported by the vertical main shaft 67 having a bearing in the casing forming the discharge conduits 68, 64, the upper extremity of the shaft 67 being directly or indirectly associated with a suitable energy absorber. The impeller 60 and the conduits leading to and from the same are inclosed by a sectional casing the sections of which are readily removable in order to permit assembly and dismantling of the unit, and the lower portion of which in the specific embodiment shown, co-operates with the concrete foundation to form the inlet conduit 62 and the transition space 63.

During normal operation of the installation specifically illustrated in Fig. 9, the guide vanes 5 are set to produce the desired speed of operation of the turbine. The liquid is admitted horizontally inwardly through the inlet conduit 2 and the spaces between the guide vanes 5, thus creating streams which whirl about the turbine axis. The whirling liquid admitted to the transition space 3 has its course deflected from inward to substantially vertically downward by the stationary guiding wall 6. In the transition space 3 the individual spirally advancing streams of liquid delivered past the guide vanes 5 are also united to form a single axially progressing and accelerating whirling mass of liquid which advances toward and enters the impeller 10. In the impeller 10 a portion of the whirl energy is converted into useful work causing rotation of the impeller 10 and of the shaft 7. The longitudinal curvature and transverse twisting of the impeller vanes, effects efficient conversion of the energy in the impeller without undesirably restricting the discharge flow. The liquid is eventually delivered from the impeller 10 past the lower and the peripheral edges of the vanes 11 into the diffusing conduit 8 wherein a portion of the remaining velocity or whirl energy is converted into pressure energy. From the diffusing conduit 8 the whirling liquid is delivered into the spiral collecting and diffusing discharge conduit 4 wherein another portion of the velocity or whirl energy is converted into pressure energy. The liquid is eventually delivered from the collecting and diffusing discharge conduit 4 with only sufficient velocity energy to produce a flow into the tail-race. In this installation the degree of whirl and the quantity of the liquid admitted to the impeller 10 may be varied by either manual or automatic adjustment of the guide vanes 5. The liquid is delivered to the impeller 10 as a substantially axially progressing solid whirling mass and is delivered from the impeller 130

4
into the diffusing conduit 8 in the direction of its major velocity component. The free discharge of liquid from the conduit 8 into the collecting conduit 4 is effected by centrifugal force, all of the conduits and passages leading to and from the turbine being so constructed that smooth hydraulic passages inducing minimum friction losses, are provided.

10 During normal operation of the inverted installation specifically illustrated in Fig. 10, the liquid is admitted to the spiral inlet conduit 52 through a suitable valve, not shown, whereby the quantity of liquid admitted may be controlled. In the spiral inlet conduit 52 the liquid is caused to whirl about the central axis of the unit. The whirling liquid is then delivered into the transition space 53 wherein its course is deflected from inward to vertically upward by the stationary guiding cone 56. The transition space 53 also serves to augment the velocity of the whirling mass of liquid and causes the liquid to progress substantially axially as a solid stream toward the inverted impeller 50. In the impeller 50 a portion of the whirl energy is converted into useful work and causes rotation of the impeller 50 and the shaft 57. The longitudinal curvature and transverse twisting of the impeller vanes, effects efficient conversion of the energy in the impeller 50 without undesirably restricting the delivery of liquid from the impeller. The liquid is eventually delivered from the impeller 50 past the upper and the peripheral edges of the impeller vanes, into the diffusing conduit 58 wherein a portion of the remaining velocity or whirl energy is converted into pressure energy. From the diffusing conduit 58 the whirling liquid is delivered into the spiral collecting and diffusing discharge conduit 54 wherein another portion of the velocity or whirl energy is converted into pressure energy. The liquid is eventually delivered from the collecting and diffusing discharge conduit 54 with only sufficient velocity energy to produce a flow into the tail-race. In this installation the quantity of liquid admitted to the impeller 50 may readily be varied with the aid of a valve and the degree of whirl will vary according to variations in speed of the impeller and to variations in the quantity of liquid admitted. The liquid is delivered to the impeller 50 as a substantially axially progressing solid whirling mass and the delivery from the conduit 58 into the final diffusing conduct 54 is effected by centrifugal force, all of the conduits and passages leading to and from the turbine being so constructed that smooth hydraulic passages are formed.

15 During normal operation of the inverted installation specifically illustrated in Fig. 11, the guide vanes 65 are set to produce the

desired speed of operation of the turbine. The liquid is admitted horizontally inwardly through the lower inlet conduit 62 and the spaces between the guide vanes 65, thus creating streams whirling about the turbine 70 axis. The whirling liquid admitted to the transition space 63 has its course deflected from inward to vertically upward by the stationary guiding cone 66. In the transition space 63 the individual spirally advancing streams of liquid delivered past the guide vanes 65 are also united to produce a single axially progressing and accelerating whirling mass of liquid which advances upwardly and enters the impeller 60. In the 75 impeller 60 a portion of the whirl energy of the liquid is converted into useful work and produces rotation of the impeller 60 and of the shaft 67. By virtue of the longitudinal curvature and transverse twisting of 80 the impeller vanes and of the location of the wall 70 closely adjacent to the lower part of the periphery of the impeller efficient conversion of the energy is effected in the impeller 60 without undesirably restricting 85 the discharge flow. The liquid is eventually delivered from the impeller 60 past the upper vane edges and the upper portions of the outer extremities of the vanes, into the diffusing conduit 68 wherein a portion of 90 the remaining velocity or whirl energy is converted into pressure energy. From the diffusing conduit 68 the whirling liquid is delivered into the spiral collecting and diffusing discharge conduit 64 wherein another portion of the velocity or whirl energy is converted into pressure energy. The liquid is eventually delivered from the collecting and diffusing discharge conduit 64 with only sufficient velocity to produce a 95 flow into the tail-race. In this installation the degree of whirl and the quantity of liquid admitted to the impeller 60 may be controlled by either manual or automatic adjustment of the guide vanes 65. The liquid is delivered to the impeller 60 as a substantially axially progressing solid whirling mass and is delivered from the impeller into the diffusing conduit 68 in the 100 general direction of its major velocity component. The confining wall 70 aids in retaining the liquid within the impeller for a longer period of time. The discharge of liquid from the discharge conduit 68 into the collecting conduit 64 is effected by 105 centrifugal force, and all of the conduits and passages leading to and from the turbine are constructed to provide smooth hydraulic 110 passages.

115 In ordinary installations, the capacity of 120 a turbine of predetermined design, is limited by the discharge area and the velocity of flow attainable in the discharge passages. With the present invention, the discharge area is enormously increased by avoiding 125 130

- peripheral inclosure of the impeller and thus permitting the liquid to discharge freely both axially and radially outwardly from the impeller. If the delivery of liquid from a unit such as disclosed in Figs. 9 and 10, is found undesirably free, a partial peripheral inclosure such as illustrated in Fig. 11, may be found desirable. It may also be desirable in some instances to produce complete diffusion in the decelerating discharge conduit 8, 58, 68 and to form the spiral discharge conduit 4, 54, 64 merely as a constant velocity collecting conduit. It may also be desirable in some instances to form the discharge conduit 8, 58, 68 merely as a conducting conduit, and to produce diffusion in the spiral conduit 4, 54, 64 only. These modifications are within the contemplation of the present invention which is applicable to installations of a variety of forms constructed to meet various hydraulic conditions.
- The impeller may also be modified in structure as illustrated in Figs. 1 to 8 inclusive, in order to meet various operating conditions. The use of these impellers is not confined to vertical shaft units such as illustrated, thus making the invention applicable to units wherein the shafts are disposed horizontally or otherwise. The hubs of the impellers are preferably formed to gradually guide and to conduct the liquid passing between the impeller vanes, toward the discharge conduit. The inverted settings illustrated in Figs. 10 and 11, have among others, the advantage of permitting submergence of the impeller and of reducing to a minimum the cost of the foundation structure and the length of the main shaft. The impeller in any of these units is readily accessible for inspection by merely removing one of the casing portions and the units are devoid of complicated and delicate parts which might necessitate interruption in operation.

It should be understood that it is not desired to limit the invention to the exact details of construction and of operation herein shown and described, for various modifications within the scope of the claims may occur to persons skilled in the art.

It is claimed and desired to secure by Letters Patent:

1. In combination, conduit means for producing a stream of liquid, and a turbine impeller having a central hub and vanes extending radially from said hub and located in said stream, the projected vane area of said impeller being less than the adjacent stream cross-section measured perpendicular to the impeller axis, and the vanes of said impeller being transversely twisted and radially spirally curved.
2. In combination, conduit means for producing a stream of liquid and a turbine im-

peller having vanes located in said stream, the projected vane area of said impeller being less than the adjacent stream cross-section measured perpendicular to the impeller axis, and said impeller vanes having free outer ends and being curved spirally from their inner to their outer extremities in planes perpendicular to said axis.

3. In combination, conduit means for producing a stream of liquid, and a rimless turbine impeller having vanes located in said stream, the projected vane area of said impeller being less than the adjacent stream cross-section measured perpendicular to the impeller axis, and the vanes of said impeller being transversely twisted and longitudinally spirally curved in planes perpendicular to said axis.

4. In combination, conduit means for producing a stream of liquid, and a turbine impeller having vanes located in said stream, the projected vane area of said impeller being less than the adjacent stream cross-section measured perpendicular to the impeller axis, and the outer extremities of said vanes lying in a conical surface, said vanes being spirally curved in planes perpendicular to said axis.

5. In combination, conduit means for producing a stream of liquid, and a rimless turbine impeller having vanes located in said stream, the projected vane area of said impeller being less than the adjacent stream cross-section measured perpendicular to the impeller axis, and the outer extremities of said vanes lying in a conical surface, said vanes having spirally curved generatrices lying in planes perpendicular to said axis.

6. In combination, conduit means for producing a stream of liquid, and a turbine impeller having a tapered hub and transversely twisted vanes located in said stream, the projected vane area of said impeller being less than the adjacent stream cross-section measured perpendicular to the impeller axis, and the outer extremities of said vanes lying in a conical surface converging oppositely of the taper of said hub.

7. In combination, conduit means for producing a stream of liquid, and a turbine impeller having a tapered hub and longitudinally curved vanes located in said stream, the projected vane area of said impeller being less than the adjacent stream cross-section measured perpendicular to the impeller axis, and the outer extremities of said vanes lying in a conical surface converging oppositely of the taper of said hub.

8. In combination, conduit means for producing a stream of liquid, and a turbine impeller having radiating vanes curving spirally about the rotor axis and located in said stream, the projected vane area of said impeller being less than the adjacent stream cross-section measured perpendicular to the

impeller axis, and said impeller having a hub which gradually increases in diameter from the inlet to the outlet of said impeller.

9. In combination, conduit means for producing a stream of liquid, and a turbine impeller having longitudinally spirally curved vanes located in said stream, the projected vane area of said impeller being less than the adjacent stream cross-section measured perpendicular to the impeller axis, and said impeller having a hub which gradually increases in diameter from the inlet to the outlet of said impeller.

10. In combination, conduit means for producing a stream of liquid, and a rimless turbine impeller having radially spirally curved vanes located in said stream, said impeller having a hub which gradually increases in diameter from the inlet to the outlet of said impeller.

11. In combination, conduit means for producing a stream of liquid, and a turbine impeller having transversely twisted and radially spirally curved vanes located in said stream, said impeller having a hub which gradually increases in diameter from the inlet to the outlet of said impeller.

12. In combination, conduit means for positively producing a whirling stream of liquid, and a turbine impeller having radially spirally curved vanes located in said stream, the projected vane area of said impeller being less than the adjacent stream cross-section measured perpendicular to the impeller axis.

13. In combination, conduit means for positively producing a whirling stream of liquid, and a rimless turbine impeller having transversely twisted and radially spirally curved vanes located in said stream, the projected vane area of said impeller being less than the adjacent stream cross-section measured perpendicular to the impeller axis.

14. In combination, conduit means for producing a stream of liquid and a turbine impeller having vanes located in said stream, the projected vane area of said impeller being less than the adjacent stream cross-section measured perpendicular to the impeller axis, and said impeller being formed for free discharge of liquid in both axial and radial directions, said conduit being formed to permit said free discharge from said rotor.

15. In combination, conduit means for positively producing a whirling stream of liquid, and a turbine impeller having longitudinally curved vanes located in said stream, the projected vane area of said impeller being less than the adjacent stream

cross-section measured perpendicular to the impeller axis, and said impeller being formed for free discharge of liquid in both axial and radial directions, said conduit being formed to permit said free discharge from said rotor.

16. In combination, conduit means for positively producing a whirling stream of liquid, and a rimless turbine impeller having transversely twisted and longitudinally curved vanes located in said stream, the projected vane area of said impeller being less than the adjacent stream cross-section measured perpendicular to the impeller axis, and said impeller being formed for free discharge of liquid in both axial and radial directions, said conduit being formed to permit said free discharge from said rotor.

17. In combination, a turbine impeller having non-overlapping vanes, conduit means formed to positively produce a whirling stream of liquid and to deliver said stream axially toward said impeller, and means for effecting free discharge of whirling liquid from said impeller in both axial and radial directions.

18. In combination, a turbine impeller having non-overlapping longitudinally curved vanes, conduit means for producing a whirling stream of liquid advancing axially toward said impeller, and means for effecting free discharge of liquid from said impeller in both axial and radial directions.

19. In combination, a rimless turbine impeller having non-overlapping transversely twisted longitudinally curved vanes, conduit means for positively producing a whirling stream of liquid advancing axially toward said impeller, means for conducting liquid away from said impeller in both axial and radial directions and flow decelerating means communicating with said conducting means.

20. In combination, a rimless turbine impeller having non-overlapping transversely twisted longitudinally curved vanes, conduit means for positively producing a whirling stream of liquid advancing axially toward said impeller, means for conducting liquid away from said impeller in both axial and radial directions, means for initially decelerating the flow and for conducting liquid away from said impeller, and a spiral collecting chamber for receiving and for finally decelerating the flow of liquid from said collecting means.

In testimony whereof, the signature of the inventor is affixed hereto.

EDWIN H. BROWN.
